(57) **CLAIM**

The ornamental design of an engine precleaner adapter, as shown and described.

DESCRIPTION

FIG. 1 is a front perspective view of a dual engine precleaner adapter showing our design;

FIG. 2 is a bottom plan view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a front elevational view thereof; and,

FIG. 8 is an alternative front perspective view of the dual precleaner adapter illustrating precleaners in phantom attached to the dual engine precleaner adapter of the present invention.

The broken lines shown in the drawings are included for the purpose of illustrating environment structure and form no part of the claimed design.
